HEAD FASTENER FOR DIP BARRELS

Walter J. McGarr, Cordele, Ga., assignor to McGarr-Turner Company, Cordele, Ga., a partnership composed of W. J. McGarr and W. R. Turner

Application July 28, 1942, Serial No. 452,659

1 Claim. (Cl. 220—40)

My invention relates generally to so-called dip barrels, and more particularly to fasteners for the heads of such barrels and other containers such as are used in collecting turpentine gum for transportation to stills.

The invention is designed with the primary objects in view of providing a simply constructed, inexpensive fastener for the heads of such barrels adapting the heads for quick, easy and positive attachment to the barrels and obviating accidental displacement of the heads in handling of the barrels, and which further provides for easy removal of the heads, is strong and durable and fool-proof.

Other and subordinate objects are also comprehended by my invention, all of which, together with the precise nature of my improvements, will be readily understood when the succeeding description and claim are read with reference to the drawings accompanying and forming part of this specification.

In said drawings:

Figure 1 is a fragmentary view in vertical transverse section illustrating my improved fastener applied.

Figure 2 is a view in bottom plan of the head and fastener,

Figure 3 is a fragmentary view in top plan of the head, fastener and barrel.

Figure 4 is a view in transverse section taken on the line 4—4 of Figure 3 and drawn to an enlarged scale.

Figure 5 is a similar view taken on the line 5—5 of Figure 1, and

Figure 6 is a view in end elevation of the bushing.

Referring to the drawings by numerals, by way of exemplification, my improved fastener has been shown therein as applied to the disc-type wooden head 1 of a usual dip barrel 2 having the internally beveled mouth end 3, and an internal laterally extending ring 4 mortised into the barrel below the bevel, as at 5, and at the mouth end thereof to form a flat seat for said head 1. The ring 4 is provided with a pair of diametrically opposite edge notches 4' therein.

According to my invention, the head 1 is provided with a diametrical, flat top, clamping bar 6 having extending along the bottom thereof a reinforcing rib 7 gradually reduced in thickness toward each end of the bar. A central hub 8 is provided on the bar 6 and a recess 9 in the rib 7 below said hub. The bar 6 is of the requisite length to underlie at both ends thereof the ring

4 with said ends clearing the side of the barrel 2. At one side of the head 1, a U-type stirrup 10 of flat metal is secured to the under face of the head 1 to depend therefrom adjacent the ring 4 and loosely straddle one end of said bar 6. The stirrup 10 may be secured to the head 1 by end ears 11 on the stirrup and screws 12 extended through the ears into said head.

Suitably secured in the head 1, as by bolting, 10 as shown, is an axial metal bushing 13 having a radial, beveled, circular flange 14 at the upper end thereof fitting flush against the top of the head 1, the upper end of the bushing forming a flat seat 15.

A bolt 16 is journaled in the bushing 13 with a working fit and has its lower end threaded through the hub 8 of the bar 6 and extending into the recess 9 clear of the bottom of said recess. The bolt 16 is provided with an annular collar 17 fitting flush on the seat 15 and a squared head 18 above said collar 17.

A laterally extending, short hand lever 19 is provided for turning the bolt 16 and which is attached to the head 18 by means of a forked yoke 25 end 20 on the lever straddling said head and fitting flush against the head and over the collar 17 with a pin 20 extended therethrough and through said head.

The manner in which the described fastener is 30 operated to attach and detach the head 1 will be readily understood. With the bolt 16 turned in the proper direction to widely space the clamping bar 6 from the head 1, said head is placed on the ring 4 so that the ends of the bar 35 6 may be inserted downwardly under the ring 4 by way of notches 4'. The head 1 is then rotated on the ring 4, in either direction, until the ends of the bar 6 are out of registration with the notches 4'. Now, by turning the bolt 16 in 40 the proper direction, the bar 6 may be tightly clamped at both ends against the under side of the ring 4 and the head 1 against the upper side of said ring. To detach the head 1, the described procedure for attaching is substantially 45 reversed, as will be clear.

As will now be seen, the collar 17 and seat 15 coact to form a seal preventing accumulation of foreign matter between the bushing 13 and bolt 16 preventing operation of the bolt, and the recess 9 prevents the bolt 16 from jamming against the bar 6 when said bolt is turned to clamp the bar against the ring 4.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claim.

What I claim is:

The combination with a barrel having an annular inwardly extending ledge in the mouth thereof, of a disk-like head for the barrel adapted to seat flat on said ledge, and means to fasten said head against the ledge comprising a diametrical bar extending along the bottom side of said head of the requisite length to extend at both ends beneath said ledge, means to adjust said bar into and form clamping relation to said

ledge comprising an axial bushing in said head, a bolt extending through said bushing with a working fit and threaded into said bar, a shoulder on said bolt coacting with one end of said bushing to prevent movement of the bolt inwardly of the barrel, a crank lever on one end of the bolt for turning the same, and means on said head for restraining the bar against rotation by said bolt and providing for limited movement of the bar toward and from the ledge, said last means comprising a stirrup attached to the bottom side of the head and straddling one end of said bar, said end of the bar being slideable toward and from the ledge in said stirrup.

WALTER J. McGARR.
